A. A. FOURNIER

SOFT CUFF

Filed May 11, 1925

Inventor
Albert A. Fournier

By E. A. Bond
Attorney

UNITED STATES PATENT OFFICE.

ALBERT A. FOURNIER, OF OTTAWA, ONTARIO, CANADA.

SOFT CUFF.

Application filed May 11, 1925. Serial No. 29,586.

To all whom it may concern:

Be it known that I, ALBERT A. FOURNIER, a citizen of the Dominion of Canada, residing at Ottawa, in the county of Carleton, Province of Ontario, Dominion of Canada, have invented certain new and useful Improvements in Soft Cuffs, of which the following is a specification.

This invention pertains to certain new improvements in soft cuffs.

The present invention pertains to that type of soft cuff in which opposite edges are free for rolling movement, and in the present instance such type of cuff is open at the ends for the ready introduction of a drying member, each end of the cuff being provided with aligned button-holes to receive cuff buttons, the stitches of said button-holes, however, not extending through from side to side of the cuff, but being disposed in the ply or plies of material upon opposite sides of such cuff. The cuff thus formed is non-revoluble in use, the wearing edges left free for such rolling movement being permanent in use in contra-distinction to being free for revolution to bring different wearing surfaces of the cuff into different operative positions. The cuff buttons employed serve to thus limit the revolution of the cuff at the wearing edges.

The cuff may be formed of a single ply of material or of multiple plies, as may be desired, the mode of use and non-revolubility of the cuff with permanent edges being maintained in all forms in which the invention may be embodied in practice.

The invention is clearly illustrated in the accompanying drawings, which with the numerals of reference marked thereon form a part of this specification; and in which—

Figure 1 is a perspective view of my improved cuff, one of the open ends thereof being slightly turned up for the purpose of illustration.

Fig. 2 is a longitudinal section through the same as on the line 2—2 of Figure 1.

Fig. 3 is a cross section as on the line 3—3 of Figure 2.

Fig. 4 is a substantially central longitudinal section through a cuff made of a single ply.

Fig. 5 is a cross section as on the line 5—5 of Figure 4.

Like numerals of reference indicate like parts throughout the several views.

In carrying out my invention I may make the tubular body portion in any suitable well known way. It may be made in tubular lengths afterward cut off to provide the suitable length cuff, or each separate cuff may be individually formed. This tubular member may be of one single integral piece without seam, or as shown in the present instance, it may be made of a single piece of material having the adjacent edges thereof folded within each other, as seen at 1—1 in Figure 3, and the edges united by suitable stitches 2, and the tubular member then turned inside out so that the seam 3 is hardly visible.

The tubular member thus constructed, indicated by numeral 4, as a whole may or may not be provided with a lining. In Figures 1, 2 and 3, I have shown such lining 5, the free edges of which over-lie the inturned edges of the tubular member, as seen best in Figure 3.

In Fig. 4 the tubular member 4^a is employed without a lining, the same when formed of a single piece having its abutting edges turned back, as seen at 6, in Figure 5 and stitched as at 7, and the tubular member then turned inside out so as to bring the portions 6—6 within the tubular member.

In all instances the ends of the material forming the cuff are turned inward to form a hem 8, suitable stitches 9 being employed at such ends, as seen clearly in Figures 1 and 2.

Each end of the cuff is formed with two aligned button-holes 10 and 11, one upon each side of the cuff as seen in Figures 1, 2 and 4, but the button-hole stitches of these button-holes do not extend through from side to side of the cuff so as to connect the opposite sides together, but as shown clearly in Figures 1, 2, and 4, there is no connection between the opposite faces of the cuff at these points. This leaves the opposite edges free for rolling movement as will be clearly understood upon reference to Figures 1, 3 and 5 where 12 is employed to indicate the rounded or rolling edge.

In practice, however, when the cuff is applied to the shirt and the cuff buttons pass through the button-holes in the usual manner, these edges are free for rolling movement within restricted scope so that the cuff as a whole is non-revoluble in use, the wearing edges 12—12 thereof being

permanent in use. This provides for the reversal of the cuff after one edge has become worn or soiled.

In addition to the advantages just above described, a cuff thus constructed may be readily washed and stretched and dried, dispensing with the necessity of ironing, the open ends of the cuff permitting of the ready insertion of a substantially flat member without obstruction, by which the cuff may be stretched or laid in its flat condition and thus insuring that the cuff shall be perfectly smooth when dried, after which the stretching plate or member may be readily withdrawn.

In the present instance the button-hole stitches at the ends are shown as being at their outer ends extended through the hem of the cuff, as shown clearly at 13 in Figures 2 and 4. This serves to materially strengthen the cuff at the ends where the wear and strain occurs by reason of employment of the cuff buttons.

What is claimed as new is:

1. As an improved article of manufacture, 25 a soft cuff of tubular form, with opposite edges free for rolling movement, the cuff being open at the ends and each end provided with two opposed registering button-holes to receive cuff buttons, the stitches of the 30 button-holes upon one side of the cuff being disconnected from the other side of the cuff, the said cuff being held against revoluble movement in use.

2. As an improved article of manufacture, 35 a soft cuff of tubular form, with its opposite edges free for rolling movement, the cuff having its opposite sides free and unattached to each other, the cuff thus being entirely open at the ends and each end provided with 40 two opposed registering button-holes only to receive cuff buttons, the said cuff being held against revoluble movement in use.

In testimony whereof I affix my signature.

ALBERT A. FOURNIER.
